William Percy Smith
By Cushman, Bryant & Co.

UNITED STATES PATENT OFFICE.

WILLIAM PERCY SMITH, OF SOUTHWARK, LONDON, ENGLAND, ASSIGNOR TO W. P. SMITH SPORTS COMPANY LIMITED, OF HOLBORN, LONDON, ENGLAND.

GOLF CLUB.

Application filed October 12, 1920. Serial No. 416,468.

To all whom it may concern:

Be it known that I, WILLIAM PERCY SMITH, a subject of the King of Great Britain, residing at 11 Brook Street, Kennington

5 Road, Southwark, in the county of London, England, have invented certain new and useful Improvements in Golf Clubs, of which the following is a specification.

This invention relates to the manufacture of golf clubs and the like, of the kind in which the head is unprovided with a socket for attaching the shaft thereto, the latter being inserted directly into an open recess in the said head.

15 According to my invention I form the head of the socket at the heel portion thereof with an open ended slotted recess advantageously of rectangular shape extending from top to bottom thereof, and

20 the end of the shaft is correspondingly shaped to fit and completely fill said recess wherein it may be secured by glue. The said recess has substantially the same width and depth in a direction measured from the

25 heel towards the toe of the head as the diameter of said shaft. Suitable means such as a pin or screw is preferably passed through the head of the club and the end of the shaft to retain the portions of the head

30 formed by the said recess securely to the end of the said shaft.

In order that the said invention may be clearly understood and readily carried into effect, I will now describe the same more 35 fully with reference to the accompanying drawing, in which:—

Figure 1 is a sectional elevation of the head of a golf club constructed in accordance with my invention.

40 Figure 2 is a section taken along the line 1—1 of Figure 1.

Figure 3 is a similar view to Figure 2 showing other means of retaining the portions together.

Figure 4 shows the head separate from the shaft and

Figure 5 shows the shaft separate from the head.

A is the head and B is the lower part of the shaft. In the example shown the head A is formed with the rectangularly shaped recess a (see Figure 3) for the reception of the end b of the shaft which is correspondingly shaped to fit and completely fill the said recess a, which has substantially the same width and depth in a direction measured from the heel towards the toe of the head as the diameter of said shaft. The end b of the shaft is adapted to be secured to the head by being glued into the recess a. C is a pin of wood which passes through the holes a', a' formed in the head and the hole b' in the shaft and serves to firmly retain the parts in place. In some cases the said wooden pin may be substituted by a metal screw D which would act to clamp the walls of the recess a in the head of the club to the sides of the end b of the shaft (see Figure 3).

What I claim and desire to secure by Letters Patent of the United States is:—

A golf club consisting in the combination of a wooden head having an open ended slotted recess in the heel thereof extending from top to bottom, a wooden shaft shaped to fit and completely fill said recess which has substantially the same width and depth in a direction measured from the heel towards the toe of the head as the diameter of said shaft and means for securing the head and shaft together.

WILLIAM PERCY SMITH.
